MOLDED TOY ANIMAL FIGURE

Don A. Winton, Pasadena, Calif., assignor to
J. L. Prescott Company, Passaic, N.J.

Filed July 22, 1969, Ser. No. 18,338

Term of patent 14 years

Int. Cl. D21—02

U.S. Cl. D34—2

FIG. 1

FIG. 2

FIG. 3

FIG. 1 is a side elevational view of a molded toy animal figure showing my new design;

FIG. 2 is a top plan;

FIG. 3 is a front elevation; and

FIG. 4 is a rear elevation.

I claim:

The ornamental design for a molded toy animal figure, as shown.
